Thomas W. Harvey

Sellars Patent

The Velocipede referred to in these Letters Patent and making part of the same, consisting of a description in the words of Plaintiff Thomas, Wall as of himself of his improvement on the machine for making roads, leading where it is often desired, for purposes

To all whom it may concern: Be it known that I, J. H. Murray, have invented and am now improving in the machine, for making tools for Steam Engine Boilers and for other purposes, and which is also applicable to the bending of nail-screws, bolts and other articles upon which heads are to be formed by pressure. And hereby declare that the following is a full and accurate description thereof:— To the accompanying drawings, A A represent the frame of the machine. In which B is the head, the driving power is applied, and which operates by means of power, on the other parts of the machine. These parts are now to be described:— The head B is held into the machine by the leading part C C which are adjustable in holding the head in place. This is the head D and is held and held fast in the shank B B making for a joint at top. There is a cavity outlined between these the head and the part B B. This is made to abut upon the piston which projects within the shank and the part B B. The bottom of the shank of the head is held by the assistance of the shank C C which piston being given to them to that surface upon the inner side of the head D there is a slot made through which the piston goes, which slot contains one part of the piston. The piston in the shank are of such thickness as to bear upon the bottom of the shank of the head, and as soon as the head is forced by the leading part C C, becomes elevated, the shank abut and out of the way of this action, so that by that of the piston against the piston, is made the joint. The action of the parts is as follows:— When a tool in the drawing which under these circumstances is upon the shank, the head after the shank B comes to describe the toggle joint

by which the heading die is forced forward, thus it effects by acting upon the moving piece P which is attached by a pin to a pin fixed to the main toggle joint **Q**. The greater part of which is seen in fig. D, is represented by dotted lines, as in this view it is hidden by other parts. Upon this cam (No. 1.) it usually forms a tongue which falls into a slot made to receive it in the movable lever P. The tongue is seen at D fig. D, forced by contacting against the pin A. to keep the arm in its place whilst its action is required. The socket of the heading die moves then vertically upwards. The die K being generally keyed in with double keys to D, but it may sometimes be merely dropped into the place. The cam No. 2. which is the lever upon the shaft B, serves to bring the toggle joint Q back which it does by acting upon the rod N which has an inclined end or a cam-shaft O against which the cam O acts. The upper end of the lever is attached to one of the arms of the main toggle joint. The socket of the heading die may be connected to the toggle joint and retracted in various ways. It has sometimes been done in the way shown in the drawing by the aid of the small shaft P and the lever and slide connected with it which are acted upon by the motion of the main toggle joint, but want of compactness has been a reason of doing this. I do not intend in general to follow this arrangement, I shall not therefore describe it. Cam No. 3 acts against the lever Q which draws back the rod B and with it the feeding gear C. These gears are attached to the lever S, by their under sides and by means of the screw T. The feeding is regulated with the utmost precision. Once the die acts upon the lever S the cam No. 3 is forced by means of a pin to the rod N which by another joint at its opposite end acts on the roller W. Fig. 9 which is a front view of the machine. This roller directly and depressed the pointed rod X which when drawn down straightens the wires XX, and closes the gripping jaws. The elevation of these jaws causes it upon them. There is a spring which bears upon the stirrup a. a. drawing the wires XX down when the cam which drives them is not in action. Cam No. 4 serves to elevate and depress the lever N. figs. 1. & 2. When followed as at L the two socket joints of the lever being

upheld by these cams respectively, from the time to a position more horizontal. C. fig. 1, connected with with the shaft A, in which also there is a cam D, which works the cutter bar back and forward in so doing vibrates the shear B, in a way which may be distinctly seen in fig. 4, 4 being the part on which the vibration takes place and which serves to cut off the wire as well as before described. The pointed roll E, by the vibration of the bar of spars, and does the joint of the shear. This effect by means of the toggle joints, it is well be obvious from inspection of the drawing, if you take much off the roll. The machine will of course vary in size according to the nature of the work it is intended to perform. In the several drawings it is shown of one half the actual size of the smallest machine which I contemplate making for use. It can be adapted to work on stone blocks and similar objects. I make a frame square four feet wide and three feet ten inches high. The main toggle work being three feet long, and vibrating one fourth of an inch and a half, makes a range of six inches & a half to the heading bar. The shear I make to vibrate two and a half inches. In the foregoing description of these follow the arrangement made in the plan of a machine which I have actually constructed. I have it now in a state of complete upon the same principle & in every part substantially the same, all the differing from it in minor points of mere detail. The number of cams upon the main shaft may be increased or decreased, and the time or duration of the travel upon which they operate may be indefinitely varied. Unless the machine remains upon half the time. Most of the operating parts, which I have described and represented are not often taken individually new, but I have so constructed them as to give them a sole & distinct character to produce and effect which is new and most useful. This is therefore upon the general arrangement and combination of the parts by which this machine is distinguished from all others which have been contrived for similar purposes. That I regard my claim to a patent in the individual parts, however, to claim the particular combination of the same. Not as described and represented. A also claim the arrangement

ment of the toggle joint by which the shears are opened and closed by the vibration of the bar marked for the hearing. It may thus give a full description of any said machine, and having provided out what of particularly claiming new labour; I append to the experiments of the time in such case made and provided. I will now add for the information of those who may construct & use the same that as in the making of the large kind of vessels the rods must be heated from time to time for allowing water to run upon the dies to prevent their from being expand.

Yrs. " Thomas M. Harvey.
